UNITED STATES PATENT OFFICE.

FLOYD SMITH, OF DOUGLAS, ARIZONA.

MACHINE FOR AFFIXING AND CANCELING STAMPS.

1,195,115.

Specification of Letters Patent. Patented Aug. 15, 1916.

Application filed July 28, 1915. Serial No. 42,277.

To all whom it may concern:

Be it known that I, FLOYD SMITH, a citizen of the United States, and a resident of Douglas, in the county of Cochise and State 5 of Arizona, have invented a new and Improved Machine for Affixing and Canceling Stamps, of which the following is a full, clear, and exact description.

My invention is more particularly de- 10 signed for affixing and canceling stamps on parcel post packages.

An object of the invention is to provide a machine for the indicated purpose, comprising a series of units separably operable to 15 affix stamps of a particular denomination and cancel the same after having been affixed; to provide for automatically feeding the stamps from a roll and severing the same as the stamp is applied and canceled; and 20 to provide a machine in which the units are adjustable in unison, to various heights, to suit packages of varying sizes.

The invention also has for its purpose to 25 provide a machine of the indicated character, improved in various particulars, whereby to insure accuracy of the operations, and in which the different elements are assembled in compact form.

The novel features entering into the practical embodiment of the invention, serve to 30 effectively and conveniently carry out the purpose of the invention, as will be herein-after more particularly explained.

Reference is had to the accompanying 35 drawings forming part of this specification, in which similar characters of reference indicate corresponding parts in all the views, and in which:

Figure 1 is a front elevation of a machine 40 embodying my invention, the casings of certain of the units being removed; Fig. 2 is an end elevation; Fig. 3 is a plan view of the machine as shown in Fig. 1; Fig. 4 is an enlarged longitudinal vertical section at the 45 forward end of a unit; Fig. 5 is a view similar to Fig. 4, but with the parts in different positions; and Fig. 6 is a sectional plan view of the mechanism with the parts in the position shown in Fig. 4.

In constructing a machine embodying my 50 invention, in accordance with the illustrated example, a series of units 10 are provided for affixing and canceling stamps of different dimensions. The several units are supported 55 on standards 11 on a suitable base 12. In order to provide for the vertical adjustment

of the several units to accommodate packages of different sizes therebeneath, the respective units are mounted on a transverse bar or rod 14 which is provided with yokes 60 13 at the ends thereof having sliding engagement with standards 11. The bar 14 has blocks or equivalent means, 15, thereon which are suitably secured to the casing 16 of each unit 10. The yokes 13 are suspended 65 by straps 17 or other flexible elements which have connection with winding drums 18, each drum being under the influence of a coil spring 19 therein. In fixed relation to each drum is a ratchet wheel 20 engaging 70 with which is a double pawl or pallet 21 pivoted between its ends as at 22 to the standards 11. The ratchet wheel has a suitable handle 23 and the pawl a handle 24 for manipulating the same, to raise or lower the 75 yokes 13.

On each unit 12 is an operating handle 25 arranged for vertical movement. Preferably the handle is tubular and slides on a tubular post 27 secured to a cross-member 80 26 of the casing 16, the said tube and handle housing a spring 28 for elevating the handle after a depression thereof.

In fixed relation to each handle 25 to be moved vertically therewith is a U-shaped 85 frame member 29, the side members of which have forwardly extending arms 30. A cross-bar 31 extending between the side arms 30 passes through a slot 32 in a lever 33, said lever being pivoted at its upper 90 end as at 34 to a forwardly extending fixed arm on the cross piece 26 of the casing 16. The lever 33 serves to actuate the slide 36 carrying a clamp for gripping a postage stamp, and the slot 32 of the lever is so 95 formed that the cross bar 31 when moved vertically by the movement of the handle 25, will give the necessary movement to the said lever. It is to be observed from Figs. 4 and 5 that the slot 32 at its upper end 100 has a short member 32^a from which the slot is deflected obliquely in a rearward direction, as at 32^b, the lower portion for approximately one-half of the length of the lever being again deflected as at 32^c at 105 such an angle that it will be disposed vertically after a forward movement of the slide 36. The slide 36 moves in oblique slots 37 formed in the casing 16 at the forward end thereof near the bottom. The connection between the lever 33 and the said slide is by means of a slot and pin, there being a 110

cross bar or pin 38 on the said slide 36 passing through a slot 39 formed in a forward extension 33^a of the lever, said slot 39 running generally in the same direction 5 as the slot 32. It will thus be seen that as the cross bar 31 is carried downwardly by depression of the handle 25, the said bar upon entering the oblique portion 32^b of the slot 32, will throw the lever 33 outwardly 10 from the position shown in Fig. 4, by reason of contacting with the left hand wall of the said slot. The rocking of the lever will continue until the member 32^c of the slot is brought to a vertical position. When the 15 bar 31 is moved to the dotted line position, Fig. 5, the slide 36 will have been carried outwardly from the position shown in Fig. 4 to that shown in Fig. 5 and will have clamped and carried forwardly a postage 20 stamp, as hereinafter explained, through the medium of a resilient clamp jaw 40 secured to said slide 36 by rivets 41, or other means.

The postage stamps in roll form are carried by a roller 42, (see Fig. 2) the trunnions of which are slipped into the vertical 25 slots 42^a in the casing 16. The strip of stamps is first passed from the roller beneath guides 43 (Figs. 4 and 5) and is adapted to be yieldingly pressed against a 30 table 50 by a strip of rubber 46 carried by arms 44 which are hung on a transverse rod 45, there being arms 47 integral with the arms 44 and provided with a weight 48 to exert the necessary pressure against the 35 stamps passing over the table 50. Beneath the table 50 is a well 51 to contain water for moistening stamps. The water may be entered through an inlet 52 leading from a vertical funnel 53. A sponge or other piece 40 of absorbent material 54 is carried by a head 55 which moves through a vertical slot 51^a in the table 50 at the forward end of the latter. The head 55 is carried by a vertical rod 56, said rod being hung on the arm 57 45 through a bell crank lever which is fulcrumed as at 58 on the vertical member 59^a of a bracket 59 secured within the casing 16. The other arm 60 of the bell crank lever extends upwardly, and a spring 61^a secured 50 to the bracket 59 presses against the back of the said arm 60, tending to so rock the bell crank lever as to depress the head 55 to immerse the lower end of the absorbing material 54. In order to raise the absorb- 55 ent material 54, a lever 61 is fulcrumed between its ends as at 62 on a bracket 59 and has a fork 63 at its front end adapted to be engaged and tripped by a cross bar 64 carried by the members of the frame 29, the 60 said bar 64 moving vertically in unison with the bar 31 which operates the stamp carrying slide 36. The cross bar 64 carries a canceling stamp 65 preferably of that form which is given a turn through 180 degrees 65 as it is depressed, so that when in the raised

position its face will be brought into contact with a pad 66 on the cross bar 26, and when the said canceling stamp is lowered it will bring the face in position at the bottom of the casing 16 for canceling a postage stamp. The canceling stamp 65 has slots 67 in the sides thereof to engage fixed pins 68 whereby to give the necessary turning movement to the canceling stamp in the well known manner of stamps of this character, through the vertical movement thereof. 75

A knife 69 is mounted for vertical movement in the casing 16, being hung as at 70 to a lever 71 which is fulcrumed as at 72 in a suitable bracket 73 in the casing 16. Said lever has an upwardly extending arm 74 so that the lever is generally of bell crank form, and a spring catch 75 is arranged in connection with the arm 74 and formed 85 with a hooked end 76 to engage over the forward free end of said arm 74. The function of the spring 75 is to firmly hold the knife 69 raised above the path of movement of the postage stamp and its gripping slide 36. 90 In order to release the knife 69 and cause the same to be depressed, plate springs 77 are provided, said springs pressing at their rear ends on the rod 45 or equivalent projection (see Figs. 5 and 6) the forward ends 95 of the springs bearing against the outwardly projecting ends of a head 78, to which the knife 69 is secured, the said head being connected with its lever 71 by a shank 79. Between its ends the spring is tensioned under 100 lateral pins 80 on the casing 16. To release the knife carrying lever 71 from the spring catch 75, and permit the springs 77 to depress the knife with a quick movement, a release lever 81 is fulcrumed as at 82 to the 105 bracket 73 or otherwise and is provided near the rear end beyond the fulcrum with a lateral pin 82 adapted to frictionally engage the front edge of the lever arm 74, said front edge of the lever 74 having such a form that 110 the said arm will be cammed rearwardly by the pin 82. Adjacent to the pin 82, lever 81 carries a pivoted dog 83 which is pressed against by a spring 84 that normally tends to throw the dog toward the lever arm 74. 115 To depress the lever 81, the same is formed at its forward end with a fork 84 adapted to be received and to be tripped by the cross bar 64.

When the canceling stamp 65 is in the 120 raised position (Fig. 4) the levers 61 and 81 will be adjacent to each other and their forks will be in engagement with the cross bar 64. Upon the handle 25 being depressed and the bars 31, 64, carried downwardly, the 125 rod 31 will move in the member 32^a of the slot 32 without affecting the lever 33, but the rod 64 will carry the canceling stamp 65 downwardly and will rock the levers 61, 81. The rocking of the lever 61 will cause the 130

lateral pin 61^a thereon to move against the front cam face 60^a of the lever arm 60 and will thereby throw the lever arm 57 upwardly and raise the absorbent material 54 to the position shown in Fig. 5 approximately at the level of the table 50 to moisten a stamp passing thereover. In the continued downward movement of the bar 64 it will leave the fork 63 of the lever 61 and will 5 rock the lever 61 carrying the dog 83 and pin 82 on said lever 81 upwardly. The combined movements of the said pin 82 and dog 83 will release the catch 75 from the lever arm 74 and will permit the springs 77 to depress the knife 69, the movements being timed so that the knife will descend and sever a postage stamp after the canceling stamp has been brought down upon the same. In the downward movement of the 10 support 31 simultaneously with the bar 64, when the said bar 31 reaches the oblique portion 32^b of the slot 32, the slide 36 will move forwardly away from the table 50 and carry a stamp beneath the path of the descending 15 canceling stamp 65 prior to the said canceling stamp reaching the lowered position. The forward movement of the slide 36 is arrested when the bar 31 reaches the dotted line position, Fig. 5, so that for the remaining 20 downward movement of the bar 31 there will be no movement of the slide 36.

In order to open and close the jaw 40, I provide beneath the same a transverse cam 35 which is rockably mounted on the slide 36. In fixed relation to the cam 35 at one end thereof, is an upwardly projecting lever 87 and in the path of movement of said lever is a trip 88 pivoted as at 89 to a side of the casing 16 adjacent to the lever 33. Upon a 25 forward movement of the slide 36 the lever 87 will contact with the trip 88 to freely swing the latter to a position so that its forward edge will lie in the downward path of the bar 31. Toward the end of the downward 30 movement of said bar 31, it will contact with the trip 88 and force the same against the lever 87, thus rocking the cam 35 to a position to open the jaw 40. As soon as the lever 87 is carried rearwardly to 35 a position to grip a postage stamp at the forward end of the table 50, the said lever 87 will contact with the knife 69, giving a reverse rocking movement to the cam 35 and permitting the jaw 40 to close.

The forward end of the well 51 and the bottom of the casing 16 present surfaces at an angle to each other and serve as a gage to receive and position a package beneath the stamp affixing and stamp canceling 40 element 65 to properly receive the postage stamps.

It will thus be evident that the web or strip of postage stamps will be delivered from the roll 42 or equivalent supply means 45 and advanced to a position for the forward

end of the web to be grasped by the carrier slide 36, and the front postage stamp brought forwardly to a position beneath the element 65, which, in pressing the postage stamp onto the package, serves the dual purpose of affixing and canceling the positioned postage stamp, the knife 69 functioning at the proper time to sever the affixed stamp. The operations are completely automatic following the depression of the handle or 75 equivalent deppressible operating element 25.

Having thus described my invention, what I claim as new and desire to secure by Letters Patent, is:

1. A machine of the character described, including postage stamp supply means, a canceling stamp mounted to vertically reciprocate to and from the path of travel of the postage stamp from the supply means, an inking pad above the canceling stamp, a carrier movable transversely of the movement of the canceling stamp to and from a position to receive a postage stamp from the supply means, and a deppressible operating device arranged to actuate the canceling stamp between the ink pad and the path of travel of the postage stamp, the said operating device being connected with the said carrier to actuate the same intermittently with the canceling stamp. 95

2. In a machine of the character described, a stamp supply means, a vertically reciprocating stamp affixing device, a stamp carrier reciprocating transversely of the movement of the affixing device to and from a position to receive a stamp from the supply means, a deppressible operating device carrying the said affixing device, and a lever connected at the lower end with the carrier, fulcrumed at the upper end to rock in a vertical plane toward and from the stamp affixing device, said lever having a slot ranging lengthwise thereof, the slot presenting a portion oblique to the general direction of the lever and a lower portion parallel to the general direction of the lever, there being a member on the operating device moving in said slot to actuate the lever by engagement therewith at the oblique portion of the slot, said member moving freely along the lever at the parallel portion of the slot without affecting the lever. 110

3. A stamp applying machine including a stamp supply means, a stamp affixing device mounted to vertically reciprocate to and from the path of movement of a stamp from the supply means, a carrier mounted to reciprocate transversely to and from a position beneath the affixing device to receive a stamp from the supply means and position it beneath the said affixing device, a deppressible operating device carrying said affixing device, a lever connected with the carrier and fulcrumed on a relatively fixed support to rock in a vertical plane, a mem- 125

- ber movable with the operating device and so engaging said lever as to rock the same to and fro while the affixing device is nearing and leaving its raised position, a vertically reciprocating moistener, means controlled by the operating device to raise the moistener to the path of movement of a stamp by the carrier and release the moistener to permit it to move downwardly, a vertically reciprocating knife, spring means to depress the knife and means controlled by the operating device to raise the knife and then release it for the spring means to act.
- 15 4. In a machine of the character described, a stamp supply means, a vertically reciprocating stamp affixing device, a stamp carrier reciprocating transversely of the movement of the affixing device to and from a position to receive a stamp from the supply means, a depressible operating device carrying the said affixing device, a lever connected at the lower end with the carrier, and fulcrumed at the upper end to rock 20 in a vertical plane toward and from the stamp affixing device, said lever having a slot ranging lengthwise thereof, the slot presenting a portion oblique to the general direction of the lever and a lower portion 25 parallel to the general direction of the lever, there being a member on the operating device moving in said slot to actuate the lever by engagement therewith at the oblique portion of the slot, said member moving freely 30 along the lever at the parallel portion of the slot without affecting the lever, a vertically reciprocating moistener, a bell crank lever one arm of which carries said moistener, a lever controlled by the operating device and 35 engageable with the other arm of the bell crank lever to raise the moistener and to release the moistener and permit it to move 40

downward, a vertically reciprocating knife, spring means to depress said knife, a second bell crank lever on one arm of which said knife is suspended, a knife-controlling lever actuated by the operating device and engageable with the other arm of the second bell crank lever, a spring catch to engage the said other arm of the second bell crank lever, and means on the knife-controlling lever to release the said spring catch and permit the said spring means to depress the knife. 45

5. A stamp applying machine including 55 a stamp supply means, a vertically reciprocating stamp affixing device movable to and from the path of travel of a stamp from the supply means, a carrier movable to and from a position to receive a stamp from the supply means and adapted to locate a stamp beneath the affixing device, a depressible operating device carrying the said stamp affixing device, means to actuate said carrier by the said operating device, a resilient jaw 60 on the carrier to grip a stamp to cause it to move with the carrier, a jaw lifting device including a lever, and a pivoted trip engageable by the said lever in a forward movement thereof to rock the trip into a 65 position to be engaged by the operative device, said operating device serving to give a reverse movement to the trip for rocking said lever and opening the jaw, there being means to engage said lever and to permit 70 the jaw to close after a stamp has entered beneath the jaw. 75

In testimony whereof I have subscribed my name to this specification in the presence of two subscribing witnesses.
